UNITED STATES PATENT OFFICE.

EDWIN HEDRICK, OF KENILWORTH, ILLINOIS.

METHOD OF FIXING FINGER-PRINTS.

1,259,981.

Specification of Letters Patent. Patented Mar. 19, 1918.

No Drawing.

Application filed June 4, 1917. Serial No. 172,784.

To all whom it may concern:

Be it known that I, EDWIN HEDRICK, a citizen of the United States, residing at village of Kenilworth, in the county of Cook and State of Illinois, have invented certain new and useful Improvements in Methods of Fixing Finger-Prints, of which the following is a specification.

This invention relates to a method of fixing finger prints, and consists in a particular method of operation. By the method heretofore practised an imprint of the fingers is first made on the impression surface, after which the oily and practically invisible lines are, so to speak, developed by dusting over them a material containing a pigment so that the lines become clearly visible. To preserve these lines and to prevent smearing or obliteration, the imprint is sprayed with a fixing material, such as a solution of shellac in alcohol.

By the present method, I mix with the developing powder a latent binding or fixing agent in the form of finely powdered shellac, gum, or other suitable adhesive, and then spray onto the developed print a suitable solvent, such as grain or wood alcohol, by which means the finely powdered adhesive material is dissolved and there is formed over the print a transparent covering.

The developing powder which has heretofore been used consisted of lamp black or other pigment and a body substance, such as wheat flour. I may add the powdered shellac, gum, or other material to this powder, or may substitute for the whole or a portion of the body material, the powdered shellac or its equivalent adhesive or coating material.

The method of operation is as follows:

The fingers, if not sufficiently oily, are pressed upon specially prepared oil cards, or

rubbed upon the hair, and the oily fingers are then pressed upon paper or other suitable surface. The practically invisible prints are then dusted with the developing powder comprising the pigment and the powdered shellac, with or without additional powdered body material.

The thus developed print is then fixed by spraying thereon a solvent of the adhesive material, such as alcohol when shellac is used.

The print is thus made permanent and cannot be smeared or obliterated, as it is protected by an exceedingly thin transparent coating of the varnish formed by the solution of the adhesive in the solvent.

While I have described my invention in detail, it is to be understood that it is not limited to the particular materials specified, except as indicated in the claims.

I claim:

1. The process of making finger prints which consists in pressing the oily fingers on an impression surface, dusting the impression with a powder containing a pigment and an adhesive, and then spraying onto said impression a solvent for said adhesive.

2. The process of making finger prints which consists in pressing the oily fingers on an impression surface, dusting the impression with a powder containing a pigment and shellac, and then spraying onto said impression a solvent for the shellac such as alcohol.

In testimony whereof I affix my signature in presence of two witnesses.

EDWIN HEDRICK.

Witnesses:

WALTER F. LYNCH,
IVAN STEPHENS.
